UNITED STATES PATENT OFFICE.

HARRY L. BRADLEY, OF MILWAUKEE, WISCONSIN.

MULTIPLE SWITCH.

Application filed June 6, 1919. Serial No. 303,244.

To all whom it may concern:

Be it known that I, HARRY L. BRADLEY, a citizen of the United States, and resident of Milwaukee, Wisconsin, have invented new and useful Improvements in Multiple Switches, of which the following is a description, reference being had to the accompanying drawings, which are a part of this specification.

10 The invention relates to switches and more particularly to that type of electrical switch in which a plurality of circuits are opened or closed in successive order.

One of the objects of the invention is to 15 provide a switch in which spaced apart movable contacts mounted upon a switch arm are successively brought into engagement with cooperative fixed contacts without danger of one set of contacts being thrown in at the 20 same time as the other set.

A further object of the invention is to 25 provide a switch arm carrying spaced apart movable contacts which are successively brought into engagement with cooperative fixed contacts and to impart a rolling movement to said movable contacts as they engage the adjacent fixed contacts so as to minimize wear and deterioration of the contact surfaces.

30 A further object of the invention is to provide a switch arm carrying spaced apart movable contacts in which a single spring acts to permit yielding movement of both of said contacts.

35 A further object of the invention is to provide novel means for mounting the switch arm upon the operating shaft.

A further object of the invention is to 40 provide a switch in which movable contacts mounted on a switch arm are successively brought into engagement with cooperative fixed contacts and thereafter one set of contacts is disengaged during a further movement of the switch arm in the same direction.

45 The invention further consists in the several features hereinafter set forth and more particularly defined by claims at the conclusion hereof.

In the drawings:

50 Fig. 1 is a front elevation view of the switch embodying the invention; Fig. 2 is a side elevation thereof in one operative position; Fig. 3 is a section taken on the line 3—3 of Fig. 2; Fig. 4 is a section taken 55 on the line 4—4 of Fig. 2; Fig. 5 is a detail view of a portion of the switch arm; Fig. 6

is a side elevation of the switch in another operative position, parts being broken away and parts being shown in section; Fig. 7 is a view similar to Fig. 6, showing another 60 position of the switch; Figs. 8, 9, 10 and 11 are diagrammatic views showing the switch in different positions.

The base 6 of insulating material has contact supports 7 and 8 secured thereto by 65 screw bolts 6' and fixed contacts 9 and 10 are respectively secured to said supports.

Journal brackets 11 are secured to the base 6 in spaced relation and have sleeves 12 journaled therein. A square operating shaft 70 13 passes through the sleeves 12 and has insulating discs 15 and a square sleeve of insulating material 16 mounted thereon, said discs and sleeve being provided with apertures shaped to conform to the shape of the 75 shaft so as to turn therewith.

A part 17 of the contact carrying arm is provided with lugs 18 near one end thereof, which have notches 19 therein to engage one of the square corners of the sleeves 16 and to 80 which they are clamped by a clip 20, having threaded ends 21 passing through the part 17 and carrying clamping nuts 22, whereby the part 17 will be tightly clamped to the square sleeve 16 and will consequently turn 85 with the operating shaft 13. By using the sleeves 12 it is not necessary to provide a specially turned shaft as the square shaft such as 13 is inserted in these sleeves, which sleeves then form a bearing part for the 90 shaft to permit its being turned in the brackets 11. Furthermore, the squared shape of the shaft does away with the necessity of keying the switch arm or other parts to the shaft and permits the use of a simple clamping means such as that previously described, so that from a manufacturing point of view 95 the use of the square shaft and the connections above described is important and of advantage in that it results in saving of 100 labor and material, both in the making of the parts and their assembly.

The outer end of the part 17 is provided with ears 23 and a part 24 of the switch arm is pivotally secured to said ears by a 105 pin 25. This part 24 is in the form of a U-shaped member and secured to the transverse portion thereof by a bolt 26 is a movable contact 27 which cooperates with the fixed contact 9. A stop pin 28, and which under some instances may be a contact member, is 110 secured to the sides of the U-shaped mem-

ber 24 between the contact 27 and the pivot pin 25. A fixed stop pin 29 is secured to the base and cooperates with the stop pin 28 either as a stop member or under some conditions, as hereinafter described, as a contact member.

The part 24 is pivotally secured intermediate its ends by the pin 25 to the part 17 and the lower end 30 thereof carries a pivot bolt 31 which is out of line with the pivot bolt 25 and mounted on this bolt between the arms of the part 24 is a bushing 32 and washers 33. A contact carrying yoke 34 is journaled on the bushing 32. This yoke is made from a single piece of metal having inwardly flanged pivot openings 35 stamped therein and having a transverse portion 36 to which a movable contact 37 is secured by a bolt 38', said contact 37 co-operating with the fixed contact 10. The sides of the member 34 are bent inwardly at one end 38 and secured together with a rivet 39, said end 38 normally engaging the pin 25.

25 The sides of the member 34 have hooked portions 40 and a rod 41 has a T head 42 in which the laterally projecting portions thereof have curved surfaces 43 contacting with the curved surfaces of the hooks 40, 30 said rod passing through a slot 44 in the part 17 and carrying a spring 45 interposed between caps 46 and 47 mounted on the rod. A pin 48 passes through the rod near the end thereof to secure the caps 46 and 47 and spring 45 in position thereon. The point of connection of the rod 41 with the member 34 lies between the pivot bolt 31 and the end 38 so that the spring 45 normally acts to maintain the end 38 in engagement with the pin 25 and thus both levers 24 and 34 normally act as a unit.

40 A circuit connection is made from the base 6 to the movable switch arm by means of a flexible conductor 49 secured to a post 50 on the base and secured by a clip 51 to the bolt 31 passing through the part 24 of the movable switch arm.

45 In connection with the contacts 27 and 9 there is shown a magnetic blowout for the arc with an arc chute but as this does not constitute a part of the present invention it will only be briefly referred to here as consisting of a magnetic coil 52, plates 53 of fireproof material forming a chute, said plates being secured together by a pivot pin 54, stop pin 55 and a pin 56, and carrying conductor plates 57 on their outer sides which cooperate with the pins 54 and 56 to form the magnetic circuit adjacent the contacts 27 and 9. The chute, being pivoted on the pin 54, may be swung back so that the stop 55 will not interfere with the forward movement of the contact 27 in case it is desired to move this contact down a considerable distance. Normally, the stop 55 co-

operates with the contact 27 to allow only a limited movement for separation of said contact with the fixed contact 9.

50 Normally the spring 45, which is under a slight compression, exerts an outward pull on the rod 41 which brings the end 38 up against the pin 25 and brings a part 58 of the end 30 of the switch arm into engagement with the arm part 17 so that said parts are all connected together to move as a unit, but which provides for a movement of the part 24 about the pivot 25 against the action of the spring 45 and a movement of the part 34 about the pivot 31 against the action of said spring.

55 The first movement of the shaft 13 to swing the free end of the switch arm towards the base 6 moves the parts 17, 24 and 34 as a unit about the brackets 11 because of the arrangement and connection of these parts with each other and with the spring 45, it being noted that each of these parts, 17, 24 and 34, is a lever and as these parts move together the contact 27 on the part 24 is brought into engagement with the fixed contact 9, the parts being then in the position shown in Fig. 2. A further movement of the operating shaft in the same direction causes the contact 27 to act as a fulcrum about the contact 9, and the lever 24 swings about its pivot pin 25 so that the end 30 swings away from the lever 17 against the action of the spring while the end 38 of the lever 34 is still in contact with the pin 25 and this produces a rolling action of the contact 27 on the contact 9 and brings the contact 37 into engagement with the contact 10. Thereafter a further movement in the same direction causes the lever 34 to swing about the bushing 32 to move the end 38 away from engagement with the pin 25 against the action of the spring 45 due to the fulcruming of the contact 37 on the contact 10, the parts moving to the position shown in full lines in Fig. 6, and this swinging action produces a rolling action between the contacts 37 and 10. Thus successive contact is made between the contacts 27 and 9 and then between the contacts 37 and 10 and it will be noted that the contact 37 is at some distance from the contact 10 at the time the contacts 27 and 9 are brought into engagement with each other, so that danger of simultaneous engagement of these sets of contacts is avoided and the leverage system provides for the movement of the contact 37 into engagement with the contact 10 through a considerable distance after the first contact has been established, so that even if the contact members of the first contact should wear, there is no danger of the two sets of contacts being made at the same time.

100 In some instances it is desirable to open the first set of contacts, 27 and 9, while the second set of contacts, 37 and 10, are still

80

85

90

95

100

105

110

115

120

125

130

engaged, and this is accomplished by a further movement of the operating shaft in the same direction as before, whereby the parts are moved from the position shown in Fig. 6 to that shown in Fig. 7. This further movement brings the stop 28 into engagement with the stop 29 which causes the outer end of the lever 24 to swing outwardly to move the contact 27 out of engagement with the contact 9 while the contacts 37 and 10 are still in engagement with each other. The parts 28 and 29 may simply be employed as co-acting stops to accomplish this separation of the first set of contacts, but, if desired, a conductor may be connected to the stop 29, in which instance these parts would serve as a third set of contacts which are brought into engagement with each other after the second set of contacts are moved to operative position.

A return of the switch arm to inoperative position causes the sets of contacts to be successively disengaged in the reverse order from that of their engagement.

25 The levers 24 and 34 are toggle arms hinged together by the bolt 31 and connected to the part 17. The parts 24, 34 and 31 are of course conductors of electricity so that current passing through the conductor 49 will pass through said part and through the sets of contacts previously described.

It is to be understood that this invention is not limited to any specific form or arrangement of parts except in so far as such limitations are specified in the claims. What I claim is new and desire to secure by Letters Patent is:

1. In a switch, the combination of a pair 40 of contacts, a movable switch-arm-carrying member, pivoted switch arms operatively connected to said member and provided with contacts, and a pair of contacts engaged by said switch arms, the contact on one switch arm engaging one of said first named contacts and rolling thereon to bring the contact on the other switch arm into engagement with the other first named contact.

50 2. In a switch, the combination of a movable member, pivoted switch arms operatively connected to said member to move therewith and with respect thereto, a pair of contacts engaged by said switch arms, one switch arm engaging one of said contacts and rolling thereon to bring the other arm into engagement with the other contact, and means engaging one arm to disengage it from its cooperative contact while the other arm remains engaged with its cooperative contact.

3. In a switch, the combination of a pair 65 of contacts, a movable switch arm comprising a movable member and a lever pivotally mounted intermediate its ends on said mem-

ber, contacts operatively connected to said lever on opposite sides of its pivot and coacting with said first named contacts, and means for normally preventing movement of said lever with respect to said member but permitting movement of said lever when one set of contacts are engaged whereby subsequent movement of said member will move said lever about its point of pivotal support to bring the second set of contacts into engagement while the first set of contacts are in operative position.

4. In a switch, the combination of a movable switch arm comprising a movable member, a lever pivotally mounted intermediate its ends on said member, a contact carried by said lever, a second lever pivotally mounted on said first lever, a contact carried by said second lever, and means normally preventing movement of said levers with respect to said member, contacts respectively cooperating with the contacts on said levers, the movement of said member first bringing the contact on the first lever into engagement with the cooperative contact and thereafter moving both levers to bring the second contact into engagement with its cooperative contact.

5. In a switch, the combination of a movable switch arm comprising a movable member, a lever pivotally mounted intermediate its ends on said member, a contact carried by said lever, a second lever pivotally mounted on said first lever, a contact carried by said second lever, spring means normally preventing movement of levers with respect to said member, and contacts respectively successively cooperating with the contacts on said levers.

6. In a switch, the combination of a pair 105 of contacts, a movable switch arm carrying contacts coacting with said first named contacts, said switch arm comprising a plurality of parts relatively movable with respect to each other to successively bring the contacts on said arm into engagement with the contacts with which they cooperate, and means distinct from said contacts, engaging said arm to move one of said parts to disengage the first set of contacts after the second set are engaged.

7. In a switch, the combination of a pair 120 of contacts, a movable switch arm comprising a movable member, a lever pivotally mounted thereon, a contact carried by said lever, a second lever pivotally mounted on said first lever, a contact carried by said second lever, and means normally preventing movement of said levers with respect to said member and with respect to each other, contacts respectively cooperating with the contacts on said levers, and means engaging one of said levers to disengage one set of contacts after the other set has been engaged.

8. In a switch, the combination of a movable switch arm comprising a movable member, a lever pivotally mounted thereon, a contact carried by said lever, a second lever pivotally mounted on said first lever, a contact carried by said second lever, and a spring for normally preventing movement of said levers with respect to said member and with respect to each other, and contacts respectively successively cooperating with the contacts on said levers. 10
9. In a switch, the combination of a movable switch arm comprising a movable member, a lever pivotally mounted thereon, a contact carried by said lever, a second lever pivotally mounted on said first lever, a contact carried by said second lever, and a spring for normally preventing movement of said levers with respect to said member and with respect to each other, contacts respectively successively cooperating with the contacts on said levers, a stop on one of said levers, and a fixed stop engaging said stop to disengage the contact carried by this lever from its cooperative contact while the contact on the other lever is engaged by its cooperative contact. 15
10. In a switch, the combination of a movable switch arm comprising a movable member, a lever pivotally mounted thereon, a contact carried by said lever, a second lever pivotally mounted on said first lever, a contact carried by said second lever, and a spring for normally preventing movement of said levers with respect to said member and with respect to each other, contacts respectively successively cooperating with the contacts on said levers, a second contact on one of said levers, and a contact engaging said second contact. 20
11. In a switch, the combination of a movable switch arm comprising a movable member, a lever pivotally mounted thereon, a contact carried by said lever, a second lever pivotally mounted on said first lever, a contact carried by said second lever, and means for normally preventing movement of said levers with respect to said member and with respect to each other, contacts respectively successively cooperating with the contacts on said levers, a second contact on one of said levers, a contact engaging said second contact to disengage the other contact carried by this lever from its cooperative contact while the contact on the other lever is engaged by its cooperative contact. 25
12. In a switch, the combination of a movable member, a switch arm, a pin pivotally connecting said arm intermediate its ends to said member, a switch arm pivoted to said first named arm and having a part normally engageable with said pin, said first named switch arm having a part normally abutting said member, a spring, and means operatively connecting said spring to said second 30
13. In a switch, the combination of a movable switch arm comprising a movable member, a contact carrying lever pivotally mounted on said movable member, and a contact carrying lever pivoted with respect to said first named lever, and contacts engaged in succession respectively by the contacts on said levers on a unidirectional movement of said movable member. 70
14. In a switch, the combination of a movable member, a switch arm pivotally supported intermediate its ends upon said member, a switch arm pivotally supported intermediate one end of said first named switch arm and its pivot, and contacts carried at opposite ends of said arms. 80
15. In a switch, the combination of a movable member, a switch arm pivotally supported intermediate its ends upon said member, a switch arm pivotally supported intermediate its ends upon said first named switch arm, and means for limiting the movement of said second switch arm. 85
16. In a switch, the combination of a movable member, a switch arm pivotally supported intermediate its ends upon said member, a switch arm pivotally supported intermediate its ends upon a pivot below and out of line with the pivot for the first switch arm, means permitting both arms to move as a unit with and relatively to said movable member, and contacts carried at opposite ends of said arms. 90
17. In a switch, the combination, with spaced contacts, of a movable member, and a pair of inflexible contact-carrying switch arms operatively connected thereto to swing relatively to each other and to said member to successively bring their contacts into circuit closing relation with the cooperative contacts on a unidirectional movement of said movable member. 105
18. In a switch, the combination of a movable member, a switch arm pivotally supported intermediate its ends upon said member, a switch arm pivotally supported on one side of the pivotal connection between said first named switch arm and said member and carrying a contact, means for normally preventing movement of said arms with respect to said member and with respect to each other, and a contact on said first named switch arm on the opposite side of its pivotal connection with said member. 110
19. In a switch, the combination of a movable switch arm comprising a movable member, a lever pivotally mounted thereon, a contact carried by said lever, a second lever pivotally mounted on said first lever, a contact carried by said second lever, and a spring for normally preventing movement of said levers with respect to said member and with respect to each other, contacts re- 120
- 125
- 130

spectively successively cooperating with the contacts on said levers, a stop on one of said levers, and a member engageable with said stop.

- 5 20. In a switch, the combination of a movable switch arm comprising a movable member, a lever pivotally mounted thereon, a contact carried by said lever, a second lever pivotally mounted on said first lever, a contact carried by said second lever, and means for normally preventing movement of said levers with respect to said member and with respect to each other, contacts re-
- 10

spectively successively cooperating with the contacts on said levers, a stop on one of said levers, and a member engaging said stop to disengage the contact carried by this lever from its cooperative contact while the contact on the other lever is engaged by its cooperative contact.

In testimony whereof, I affix my signature, in presence of two witnesses.

HARRY L. BRADLEY.
